UNITED STATES PATENT OFFICE.

EDWARD S. M. MACNAB, OF MONTREAL, QUEBEC, CANADA, ASSIGNOR TO THE SAFETY CAR HEATING & LIGHTING COMPANY, A CORPORATION OF NEW JERSEY.

BERTH-LIGHT CONSTRUCTION.

Application filed May 13, 1920. Serial No. 380,971.

To all whom it may concern:

Be it known that I, EDWARD S. M. MACNAB, a subject of Great Britain, and a resident of Montreal, in the Province of Quebec, 5 Dominion of Canada, have invented an Improvement in Berth-Light Constructions, of which the following is a specification.

This invention relates to the construction of berth lights for railway cars and the like. One of the objects thereof is to provide a simple construction of the above type which shall be durable and essentially practical. Another object is to provide a construction of the above type in which the 10 light is efficiently and economically handled. Other objects will be in part obvious and in part pointed out hereinafter.

The invention accordingly consists in the features of construction and in the relation 20 of each of such features to one or more of the others thereof as will be illustratively set forth and defined in the following claims.

In the accompanying drawing in which is 25 shown one of the various possible embodiments of this invention,

Fig. 1 is a longitudinal vertical section taken on the line 1—1 of Fig. 2.

Fig. 2 is a front elevation.

Similar reference characters refer to similar parts throughout the several views of the drawings.

Referring to Fig. 1 of the drawing, there is shown at 10 a wall, which is preferably the inner member of the side of a railway car. It may hereafter be noted, however, 35 that the term "wall," unless otherwise provided, is to be broadly interpreted. It is also to be understood that this portion of the wall shown is slightly above the berth, a position ordinarily occupied by railway berth lights.

The wall 10 is provided with an aperture 11 and has fitted therein a casing 12 substantially like the form shown. This casing 45 is provided with a flange 13, preferably countersunk in the wall, so as to be substantially flush with the outer surface thereof.

Mounted within the casing 12 is an ordinary socket 14 for an electric bulb, the wiring of which is controlled by the switch 15, the details of neither of these parts being shown, as they form in themselves no portion of the present invention.

The switch 15 is mounted upon the inner

surface of the outer plate 16, through which the controlling buttons 17 project. This plate is secured as at 18 to the casing 12 and its upper portion 19 is so shaped as to form a curved rear reflector for the bulb, as hereinafter described. This reflector is secured as at 20 to the upper portion of the casing 12. The bulb 21 passed through an opening in the reflector and is threaded or otherwise secured within the socket 14. This bulb has a filament of such form as to give an iso-photometric curve substantially as indicated at 22.

It will be understood from this diagrammatic illustration that the bulb is so formed as to throw its light generally in a plane extending through the centre of the bulb and lying transversely to the axis of the socket.

Secured to the upper portion of the casing 12 as at 23 is a fitting 24, substantially of inverted U-shape, as shown in Fig. 2 of the drawings. This fitting is flanged as at 25 to interlock with a flange 26 upon an upper shade 27. The latter part is of translucent light diffusing glass and is removable as for replacement through the removal of the fitting 24. It is also to be noted that the shade 27 clears the bulb 21 by a sufficient space to permit removal and replacement of the bulb without requiring prior removal of the shade.

In the action of this device, it is to be noted the bulb throws its greatest amount of light in a downwardly and outwardly inclined direction with respect to the wall 10. Furthermore, not only is the direct radiation 90 largely concentrated in this direction, but that which strikes the reflector is also thrown back in the same general direction. The light striking the shade 27 is by no means intense and is accordingly not glaring to the eyes and yet it contributes to a soft diffused illumination of the upper portion of the car. The various parts are readily accessible and removable for the purpose of cleaning, repairing or replacement.

As various possible modifications might be made of the above invention and as various changes might be made in the embodiment above set forth, it is to be understood that all matters herein set forth or shown in the 105 accompanying drawings are to be interpreted as illustrative and not in a limiting sense.

2
What I claim is:

1. In the construction of berth lights and the like, in combination, a wall, an electric bulb formed to throw a maximum intensity of light in a predetermined direction and a lesser intensity of light in a direction substantially at right angles to said predetermined direction and mounted adjacent said wall, an inclined reflector adapted to reflect the light of maximum intensity from said bulb downwardly and outwardly with respect to said wall and a translucent diffusing member mounted to diffuse the light of lesser intensity from said bulb extending in an upwardly inclined direction from said bulb and out of the path of said downward light.
2. In the construction of berth lights and the like, in combination, a wall, an electric bulb formed to throw a maximum intensity of light in a predetermined direction and a lesser intensity of light in a direction substantially at right angles to said predetermined direction and mounted adjacent said wall, an inclined reflector adapted to reflect the light of maximum intensity from said bulb downwardly and outwardly with respect to said wall and a translucent diffusing member mounted to diffuse the light of lesser intensity from said bulb extending in an upwardly inclined direction from said bulb and out of the path of said downward light, said bulb being mounted within a recess in said wall.
3. In the construction of berth lights and the like, in combination, a wall provided with an aperture, a member mounted within said aperture and secured to said wall to

form an enclosed recess therein, a shade removably secured to the upper portion of 40
said member, a socket mounted within said member, a reflector mounted within said member, said socket being positioned between and enclosed by said reflector and 45
said first member and a bulb coacting with said reflector and mounted in said socket.

4. In the construction of berth lights and the like, in combination, a wall, an electric bulb formed to throw a maximum of light in a predetermined direction, means mounting said bulb adjacent said wall in a position with said direction inclined downwardly and outwardly with respect to said wall, a reflector adapted to reflect light from said bulb downwardly and outwardly with respect to said wall and a translucent diffusing member adapted to diffuse light passing outwardly and upwardly from said bulb.

5. In the construction of berth lights and the like, in combination, a wall, means forming a recess within said wall, an electric bulb mounted within said recess and upwardly inclined with respect to said wall, a reflector adapted to throw light from said bulb downwardly and outwardly with respect to said wall and a translucent diffusing member adapted to diffuse light passing outwardly and upwardly from said bulb and out of the path of said downward light.

In testimony whereof, I have signed my name to this specification this 26th day of April, 1920.

EDWARD S. M. MACNAB.
